HERBICIDAL SULFOALKYL ESTERS OF
PHENOXYACETATES

Milton Kosmin, Dayton, Ohio, assignor to Monsanto
Chemical Company, St. Louis, Mo., a corporation
of Delaware

No Drawing. Application April 27, 1954
Serial No. 426,026

12 Claims. (Cl. 71—2.6)

The present invention provides new and hitherto unknown sulfoalkyl esters of certain aryloxy-substituted fatty acids, methods of preparing the same, herbicidal compositions comprising the new esters, and methods of destroying or preventing plant growth in which such compositions are used.

An object of the invention is to provide improved herbicidally active compounds. Another object of the invention is to prepare esters of aryloxy-substituted fatty acids which esters are characterized by low volatility. Still another object of the invention is to provide water-soluble aryloxy-substituted fatty acid esters.

These and other objects hereinafter disclosed are provided by the following invention wherein there are prepared sulfo-esters having the formula

in which R, R', R'' and R''' are selected from the class consisting of hydrogen, chlorine and alkyl radicals of from 1 to 4 carbon atoms and in which at least one of R, R', R'' and R''' is chlorine, Y is selected from the class consisting of hydrogen, methyl radical and chlorine, X is selected from the class consisting of hydrogen and the methyl radical, z is a number of from 1 to 2, n is a number of from 0 to 14, and M is a water-solubilizing cation.

Compounds having the above formula are readily obtainable by the condensation of the appropriate hydroxy-alkanesulfonic acid or (hydroxalkoxy)alkane sulfonic acid, e. g., isethionic acid or 2-methylisethionic acid, a water-soluble salt thereof or the hydroxy ether of such an acid and a polyalkylene glycol with the appropriate aryloxy-substituted fatty acid or acyl halide thereof substantially according to the scheme:

in which R, R', R'', R''', X, Y, M and z are as defined above and Z denotes a halogen atom or the -OH radical.

One class of aryloxy-substituted fatty acids or acyl halides thereof having the above formula and useful for the present purpose are the ar-chlorinated phenoxyacetic

2

acids having from 1 to 4 chlorine atoms and having in the benzene ring thereof at least one unsubstituted carbon atom in the position ortho- to the oxy-linkage, such as 4-chloro-, 2,4-dichloro-, 2,4,5-trichloro- or 2,3,4,5-tetrachlorophenoxyacetic acid. Another useful class of aryl-oxo fatty acids of the above general formula are ar-chlorinated α -phenoxypropionic acids having from 1 to 4 chlorine atoms and having in the benzene ring thereof at least one unsubstituted carbon atom in the position ortho- to the oxy-linkage, e. g., 3-chloro-, 2,3-dichloro-, 2,4,5-trichloro- or 2,3,4,5-tetrachloro- α -phenoxypropionic acid. Still another class of suitable aryloxy fatty acids of the above formula comprises the aralkylated-ar-chlorinated phenoxyacetic acids having in the benzene ring thereof at least one unsubstituted carbon atom in the position ortho- to the oxygen linkage, e. g., 4-chloro-2-methylphenoxyacetic acid, 4,5-dichloro-2-ethylphenoxyacetic acid, 3-isopropyl-2,4,5-trichlorophenoxyacetic acid, 2-butyl-4-chlorophenoxyacetic acid, etc.

Useful compounds of the above formula also are the corresponding α -aryloxypropionic acids, i. e., the ar-alkylated-ar-chlorinated α -phenoxypropionic acids, e. g., 2-chloro-4,5-diethyl- α -phenoxypropionic acid, 3-butyl-4-chloro- α -phenoxypropionic acid, 3-n-propyl-2,4,5-trichloro- α -phenoxypropionic acid, 2-chloro-4-methyl- α -phenoxypropionic acid, 3-chloro-2,4,5-trimethyl- α -phenoxypropionic acid, etc.

Another class of useful aryloxy-substituted fatty acids having the above general formula and useful for the present purpose includes the ar-chlorinated β -phenoxypropionic acids having in the benzene ring thereof at least one unsubstituted carbon atom in a position ortho- to the oxy-linkage, e. g., β -(2-chloro-, 2,3-dichloro-, 2,4,5-trichloro- or 2,3,4,5-tetrachloro)phenoxypropionic acids.

The corresponding aralkylated-ar-chlorinated β -phenoxypropionic acids of the above general formula are likewise useful. Examples of such ar-chloro-ar-alkyl compounds are β -(2-chloro-4-methylphenoxy)propionic acid, β -(4-dibutyl-2,3-dichlorophenoxy)-propionic acid, β -(3-ethyl-2,4,5-trichlorophenoxy)propionic acid, β -(3-chloro-2,4,5-trimethylphenoxy)propionic acid, etc.

Other classes of useful aryloxy-substituted fatty acids of the above general formula are the ar-chlorinated β -phenoxysobutyric acids or the ar-chlorinated-ar-alkylated β -phenoxysobutyric acids having in the benzene ring thereof at least one unsubstituted carbon atom in a position ortho- to the oxy-linkage. Examples of the first of these classes are β -(2,4-dichlorophenoxy)-isobutyric acid and β -(2,4,5-trichlorophenoxy)isobutyric acid. Examples of the other of these classes are β -(2-chloro-4-tolyl)isobutyric acid and β -(2,3-dichloro-4-tertbutylphenoxy)isobutyric acid.

Still other classes of presently useful aryloxy-substituted fatty acids of the above general formula comprise the ar-chlorinated β -phenoxybutyric acids or the ar-alkylated-ar-chlorinated β -phenoxybutyric acids having a free ortho- position in the benzene ring, e. g., β -(2-chloro-, 2,4-dichloro- or 2,3,4,5-tetrachlorophenoxy)butyric acid or β -(4-chloro- α -tolyloxy)butyric acid or β -(3-isopropyl-2,4-dichlorophenoxy)butyric acid.

Other aryloxy-substituted fatty acids embraced by the above general formula and useful in the preparation of the present herbicidally active compounds are the ar-chlorinated or the ar-alkylated-ar-chlorinated α , β -dimethyl- β -phenoxypropionic acids having a free ortho-position in the benzene ring, e. g., α , β -dimethyl- β -(2-chlorophenoxy)propionic acid, α , β -dimethyl-(β -2,4-dichlorophenoxy)propionic acid, α , β -dimethyl- β -(2-chloro-4-isopropylphenoxy)propionic acid, α , β -dimethyl- β -(2,4-dichloro-3-methylphenoxy)propionic acid, etc.

Aryloxy-substituted chlorinated fatty acids useful for the preparation of the present herbicidally active com-

pounds are, e. g., the ar-chlorinated or the ar-alkylated-ar-chlorinated β -phenoxy chloroacetic acids, the β -phenoxy- α -chloropropionic or butyric acids, the β -phenoxy- β -chloropropionic acids or butyric acids, and the β -phenoxy- α , β -dichloropropionic or butyric acids. As examples of such aryloxy chlorinated fatty acids may be mentioned: 4-chlorophenoxychloroacetic acid, 2,4-dichlorophenoxychloroacetic acid, 2,4,5-trichlorophenoxychloroacetic acid, 4-chloro- α -tolyloxychloroacetic acid, β -(2,4-dichlorophenoxy)- α -chloropropionic acid, β -(2,4,5-trichlorophenoxy)- β -chloropropionic acid, β -(4,5-dichloro- α -tolyloxy)- α , β -dichloropropionic acid, α -(2,4-dichlorophenoxy)- α -chlorobutyric acid, etc.

Isethionic acid compounds having the above formula and reactive with the above aryloxy-substituted fatty acids to yield the present improved herbicidal compounds are isethionic acid, 2-methylisethionic acid and the water-soluble salts thereof, e. g., the alkali metal isethionates or 2-methylisethionates such as sodium, potassium or lithium isethionate or 2-methylisethionate, ammonium isethionate or 2-methylisethionate, organic amine salts of the isethionates such as the dimethylamine, the butylamine, the triethylamine, the ethanolamine, the isopropanolamine, the tri-n-propanolamine or the morpholino salts of isethionic or 2-methylisethionic acid. Hydroxy ethers of such isethionic acid compounds obtainable, e. g., by reaction of said acid compounds with ethylene glycol, polyalkylene glycols or with from 1 to 15 moles of ethylene oxide are particularly useful in the preparation of the present esters. As examples of such hydroxy ethers may be mentioned: 2-(2-hydroxyethoxy)ethanesulfonic acid and water-soluble salts thereof, the hydroxy ethers obtainable by reaction of isethionic acid or 2-methylisethionic acid, or the salts thereof with diethylene glycol, pentaethylene glycol, octaethylene glycol or pentadecaethylene glycol, etc. The useful polyalkylene glycol ethers may also be prepared by condensing from 2 to 15 moles of ethylene oxide or isopropylene oxide with 1 mole of the isethionic acid or 2-methylisethionic acid.

Compounds obtainable by the condensation of said aryloxy-substituted fatty acids and said isethionic acid compounds are, e. g., salts of 2-sulfoethyl or 2-sulfoisopropyl ar-chlorinated or ar-alkylated-ar-chlorinated phenoxyacetates, α - or β -phenoxypropionates, β -phenoxyisobutyrate, β -phenoxybutyrate or α , β -dimethyl- β -phenoxypropionates having from 1 to 4 carbon atoms in the alkyl radical and having in the benzene ring thereof at least one carbon atom in the position ortho- to the oxy-linkage.

As examples of such 2-sulfoethyl or 2-sulfoisopropyl ar-chlorinated phenoxyacetates may be mentioned:

2-sulfoethyl 2,4-dichlorophenoxyacetate
2-(sodium sulfo)ethyl 4-chlorophenoxyacetate
2-(potassium sulfo)ethyl 2,4-dichlorophenoxyacetate
2-(ammonium sulfo)isopropyl 2,4,5-trichlorophenoxyacetate

Diethanolamine salt of 2-sulfoethyl 2,4-dichlorophenoxyacetate

Diethylenetriamine salt of 2-sulfoethyl 3-chlorophenoxyacetate

Trimethylamine salt of 2-sulfoethyl 2,3-dichlorophenoxyacetate

2-(sodium sulfo)ethyl 2,3,4,5-tetrachlorophenoxyacetate

As examples of such 2-sulfoethyl or 2-sulfoisopropyl ar-chlorinated-ar-alkylated phenoxyacetates may be mentioned:

2-sulfoethyl 4-chloro- α -tolyloxyacetate
2-(ammonium sulfo)ethyl 4-chloro- α -tolyloxyacetate
2-(sodium sulfo)isopropyl 2,4-dichloro-3-ethylphenoxyacetate
2-(lithium sulfo)ethyl 2-butyl-3,5-dichlorophenoxyacetate
Dibutylamine salt of 2-sulfoethyl 2,3-dichloro-4-isopropylphenoxyacetate

Triethanolamine salt of 2-sulfoethyl 4-chloro-2,3,5-trimethylphenoxyacetate

Morpholine salt of 2-sulfoethyl 3-chloro- α -tolyloxyacetate
2-(sodium sulfo)ethyl 2-methyl-3,4,5-trichlorophenoxyacetate

As examples of such 2-sulfoethyl or 2-sulfoisopropyl ar-chlorinated β -phenoxypropionates may be mentioned: 2-sulfoethyl β -(4-chlorophenoxy)propionate

2-(sodium sulfo)isopropyl β -(3-chlorophenoxy)propionate
2-(potassium sulfo)ethyl β -(2,4-dichlorophenoxy)propionate

Isopropanolamine salt of 2-sulfoethyl β -(2,4,5-trichlorophenoxy)propionate

Triethylamine salt of 2-sulfoethyl β -(2,3,4,5-tetrachlorophenoxy)propionate

Examples of such 2-sulfoethyl or 2-sulfoisopropyl ar-chlorinated-ar-alkylated β -phenoxypropionates are:

2-sulfoethyl β -(2-chloro-4-tolyl)propionate
2-(potassium sulfo)ethyl β -(3,4-dichloro- α -tolyl)propionate

2-(sodium sulfo)isopropyl β -(4-ethyl-2,3,5-trichlorophenoxy)propionate

2-(ammonium sulfo)ethyl β -(4-butyl-2,3-dichlorophenoxy)propionate

Triethylenetetramine salt of 2-sulfoethyl β -(2,3-dichloro-4,5-dimethylphenoxy)propionate

Morpholine salt of 2-sulfoethyl β -(4-chloro-2,3,5-triethylphenoxy)propionate

Examples of presently provided 2-sulfoethyl or 2-sulfoisopropyl ar-chlorinated β -phenoxypropionates are:

2-sulfoethyl β -(4-chlorophenoxy)propionate
2-(sodium sulfo)ethyl β -(3,4-dichlorophenoxy)propionate

2-(ammonium sulfo)isopropyl β -(3,4,5-trichlorophenoxy)propionate

n-Butylamine salt of 2-sulfoethyl β -(2,3,4,5-tetrachlorophenoxy)propionate

Examples of the present 2-sulfoethyl or 2-sulfoisopropyl ar-alkylated-ar-chlorinated β -phenoxypropionates are:

2-sulfoethyl β -(2-chloro-4-n-propylphenoxy)propionate
2-(potassium sulfo)isopropyl β -(3,4-dichloro- α -tolyloxy)propionate

Triisopropanolamine salt of 2-sulfoethyl β -(2-n-butyl-3,4,5-trichlorophenoxy)propionate

Examples of the presently provided 2-sulfoethyl or 2-sulfoisopropyl ar-chlorinated β -phenoxyisobutyrate are:

2-sulfoethyl β -(2,4-dichlorophenoxy)isobutyrate
2-(potassium sulfo)ethyl β -(4-chlorophenoxy)isobutyrate

55 Diethylenetriamine salt of 2-sulfoisopropyl β -(2,4,5-trichlorophenoxy)isobutyrate

As examples of the present 2-sulfoethyl or 2-sulfoisopropyl ar-alkylated-ar-chlorinated β -phenoxyisobutyrate may be mentioned:

2-(sulfoethyl β -(4-chloro- α -tolyloxy)isobutyrate
2-(sodium sulfo)ethyl β -(2-chloro-4-ethylphenoxy)isobutyrate

Ethanolamine salt of 2-sulfoisopropyl β -(2,4-dichloro-n-butylphenoxy)isobutyrate

Examples of the present 2-sulfoethyl or 2-sulfoisopropyl ar-chlorinated α , β -dimethyl- β -phenoxy propionates are:

70 2-sulfoisopropyl α , β -dimethyl- β -(3-chlorophenoxy)propionate

2-(potassium sulfo)ethyl α , β -dimethyl- β -(2,4-dichlorophenoxy)propionate

Morpholine salt of 2-sulfoethyl α , β -dimethyl- β -(2,4,5-trichlorophenoxy)propionate

Examples of the present 2-sulfoethyl or 2-sulfoisopropyl ar-alkylated-ar-chlorinated α,β -dimethyl- β -phenoxypropionates are:

2-sulfoethyl α,β -dimethyl- β -(2-chloro-4-n-butylphenoxy)-propionate

2-(ammonium sulfo)ethyl α,β -dimethyl- β -(3,4-dichloro-o-tolyloxy)propionate

2-(sodium sulfo)isopropyl α,β -dimethyl- β -(2-isopropyl-3,4,5-trichlorophenoxy)propionate

As examples of the present 2-sulfoethyl or 2-sulfoisopropyl ar-alkylated or ar-alkylated-ar-chlorinated β -phenoxychloroacetates may be mentioned:

2-sulfoethyl 4-chlorophenoxychloroacetate

2-(potassium sulfo)isopropyl 3-chloro-o-tolyloxychloroacetate

The di-n-butylamine salt of 2-sulfoethyl 2,4,5-trichlorophenoxychloroacetate

As examples of the present 2-sulfoethyl or 2-sulfoisopropyl ar-chlorinated or ar-alkylated-ar-chlorinated β -phenoxy α -chloropropionates may be mentioned:

2-sulfoethyl β -(2,4-dichlorophenoxy)- α -chloropropionate

2-(sodium sulfo)ethyl β -(2,4,5-trichlorophenoxy)- α -chloropropionate

Triisobutanolamine salt of 2-sulfoisopropyl β -(4-chloro-2-propylphenoxy)- α -chloropropionate

As examples of the present 2-sulfoethyl or 2-sulfoisopropyl ar-alkylated or ar-alkylated-ar-chlorinated β -phenoxy- β -chloropropionates may be mentioned:

2-sulfoisopropyl β -(2-chlorophenoxy)- β -chloropropionate

2-(ammonium sulfo)ethyl β -(2,4-dichlorophenoxy)- β -chloropropionate

The morpholine salt of 2-sulfoethyl β -(4-chloro-2-ethylphenoxy)- β -chloropropionate

Illustrative of the present 2-sulfoethyl or 2-sulfoisopropyl ar-alkylated or ar-alkylated-ar-chlorinated β -aryloxy α,β -dichloropropionates are:

2-sulfoethyl β -(4-chlorophenoxy)- α,β -dichloropropionate

2-(sodium sulfo)ethyl β -(3,4-dichloro-o-tolyloxy)- α,β -dichloropropionate

The diethanolamine salt of 2-sulfoisopropyl β -(2,4,5-trichlorophenoxy)- α,β -dichloropropionate

The above compounds are prepared by employing isethionic acid or 2-methylisethionic acid or the salts thereof as the hydroxy component in the preparation of the present esters. As has been herein stated the isethionic acid compounds may be replaced by hydroxy ethers thereof, e. g., the mono- or polyethers of ethylene or isopropylene, glycol and the isethionic or 2-methylisethionic compounds. As examples of esters of the aryloxy substituted fatty acids and the monoalkylene glycol ethers of the isethionic acids may be mentioned:

2-(2-sodium sulfoethoxy)ethyl 2,4-dichlorophenoxyacetate

2-(2-ammonium sulfoisopropoxy)isopropyl β -(2-chloro-4-tolyl)propionate

The triethanolamine salt of 2-(2-sulfoethoxy)ethyl 2,4-dichlorophenoxyacetate

As examples of the esters of the present aryloxy substituted fatty acids and polyalkylene glycol ethers of isethionic or 2-methylisethionic acid may be mentioned:

The sodium salt of the ester of 2,4,5-trichlorophenoxyacetic acid and the pentaethylene glycol ether of isethionic acid.

The ammonium salt of the ester of 4-chloro-2-tolyloxy α -chloropropionic acid and the diethylene glycol ether of isethionic acid.

The isobutanolamine salt of the ester of β -(4-chloro-o-tolyloxy)isobutyrate and the decaisopropylene glycol ether of 2-methylisethionic acid.

The sodium salt of the ester of 2,4-dichlorophenoxyacetic acid and the pentadecaethylene glycol ether of isethionic acid.

In preparing the present sulfoalkyl esters I operate substantially as follows: I heat a mixture of the isethionic acid compound, e. g., isethionic or 2-methylisethionic acid or salt thereof, with the ar-chlorinated aryloxy-substituted fatty acid compound at a temperature of from, say, 100° C. to below the decomposition point of the reaction mixture, until formation of the sulfoalkyl ester has occurred. An inert diluent may or may not be employed. Since the reaction occurs by condensation of one mole of the isethionic acid compound with one mole of aryloxy-substituted fatty acid compound, equimolar proportions of the reactants generally may be employed. In practice, it may be preferable to use a slight excess of whichever component is more readily obtainable in order to assure complete reaction of the less readily obtainable reactant. The reaction may be effected at ordinary atmospheric, sub-atmospheric or superatmospheric pressures. Generally, in order to permit smooth and rapid reaction at the higher temperatures, e. g., at temperatures of from, say, 200° C. to 300° C., it is advantageous to operate at diminished pressure, say, at a pressure of from 10 to 100 mm. of mercury. Catalysts may or may not be employed. Useful catalysts comprise organic or inorganic acid or basic materials, e. g., sulfuric acid, 4-toluenesulfonic acid, sodium methoxide, etc. The reaction product, i. e., the sulfoethyl ester, is separated from the resulting reaction mixture by simply removing any unreacted constituents, e. g., by distilling, decanting, washing or extracting. Generally the use of substantially equimolar proportions of the isethionic salt and the aryloxy-substituted fatty acid compound and heating at temperatures of from 200° C. to 300° C. for a time of, say, from a few minutes to several hours, assures complete reaction of both components so that the reaction product consists of the substantially pure, crystalline salt of the sulfoethyl ester. In this case no further treatment of the product is required.

As may be apparent to those skilled in the art, use of isethionic acid or of 2-methylisethionic acid in the condensation reaction will result in the formation of the free sulfonic acid. While the free acid may be employed as the active ingredient in the formulation of herbicidal compositions, for ease in manipulation and storage, it is generally advisable to convert the 2-sulfoalkyl ester into the sulfonate. This may be effected by neutralizing the free sulfonic acid with an appropriate organic or inorganic basically reacting agent until a neutral product is obtained. Useful basic materials in the neutralizing step are alkali metal hydroxides or the basically reacting salts thereof, water-solubilizing alkyl or alkanolamines, ammonium hydroxide or basically reacting salts thereof, morpholine etc.

The present sulfoalkyl esters and the water-soluble salts thereof are generally substantially colorless, crystalline materials which are characterized by high, selective herbicidal efficiency and low volatility. In prior art, the usefulness of chlorinated phenoxy-substituted fatty acids, e. g., 2,4-dichloro- or 2,4,5-trichlorophenoxyacetic acid, in weed control has been somewhat limited in that, owing to their high volatility, they were readily transported from the unwanted weeds, upon which they had been applied, to neighboring fields of crops. The "2,4-D" or the "2,4,5-T" type of herbicides possess a selectivity of action against broad-leaved plants, and since the majority of horticultural and crop plants are also broad-leaved, the utility of such herbicides for weeding grass plots adjacent to cultivated areas was problematic. Attempts to decrease the high volatility of the aryloxyacetic acid type of herbicides by variously substituting the nucleus or by esterifying the carboxy radical have been generally unsuccessful in that lowered volatility was often accompanied by a modification of herbicidal effect and an

undesired change in the physical characteristics with respect to solubility and form.

The invention is further illustrated, but not limited, by the following examples.

Example 1

To a 1-liter reaction vessel equipped with mechanical stirrer and thermometer there was charged a mixture consisting of 246 g. (1.0 mole) of 2,4-dichlorophenoxyacetic acid (90% assay) and 148 g. (1.0 mole) of sodium isethionate. The total weight of reactor and charge was 967.3 g. The charge was melted and heating was continued to a temperature of 210° C., at which point water-pump vacuum was applied. Heating at from 210° C. to 255° C. at a pressure of about 20 mm. of mercury was continued for 45 minutes. During this time, considerable evolution of water was noted. At the end of the heating time there was a weight loss of 30.3 g. A portion of the reaction mixture was removed and washed thoroughly with acetone to remove any unreacted material. Analysis of the washed and dried product gave 18.22% chlorine as against 20.20%, the theoretical chlorine value for $C_{10}H_8Cl_2NaO_5S$, i. e., 2-(sodium sulfo)ethyl 2,4-dichlorophenoxyacetate. Accordingly, the acetone-washed product was dissolved in water, filtered to remove traces of insoluble material and slowly precipitated by gradual addition of ethanol in order to separate the water-soluble sodium isethionate. The precipitate which formed upon treatment with ethanol was filtered off and dried to give the substantially pure 2-(sodium sulfo)ethyl 2,4-dichlorophenoxyacetate, M. P. above 270° C., analyzing 19.35% chlorine. It is labelled Product I in the herbicidal evaluation tests of Example 6.

Example 2

To a 500 ml., 3-neck flask equipped with glass stirrer, thermometer and take-over head connected to a vacuum source there was charged 94.0 g. (0.338 mole based on 92% assay) of 2,4,5-trichlorophenoxyacetic acid and 50.0 g. (0.338 mole) of sodium isethionate. The temperature of the charge was raised rapidly to 200° C., and water-pump vacuum was gradually applied, so that within about 15 minutes the temperature of the reaction mixture had reached 250° C. After a total heating time of 20 minutes at a temperature of 215-255° C., and a minimum vacuum of about 40 mm. of mercury, heating was discontinued. During this time water together with a small quantity of phenol distilled off. A total weight loss of 21.6 g. of the reaction mixture was noted. By the end of the heating period the reaction mixture had begun to solidify. The liquid portion of the reaction mixture was removed, and the residual solid was washed 3 times with an excess of acetone, dried and dissolved in hot water to give an approximately 20% solution. The hot solution was filtered to remove traces of water insoluble material. The precipitate which formed in the filtrate upon cooling was filtered off, dried, washed with acetone and dried to give the substantially pure 2-(sodium sulfo)ethyl 2,4,5-trichlorophenoxyacetate analyzing 27.61% chlorine as against 27.59% the calculated value for $C_{10}H_8Cl_3NaO_5S$.

Example 3

Employing the apparatus described in Example 2, a mixture consisting of 111.5 g. (0.5 mole based on 90% assay) of 4-chloro-o-tolyloxyacetic acid and 74.0 g. (0.5 mole) of sodium isethionate was heated to a temperature of 225° C., water-pump vacuum was applied and heating was continued to a temperature of 255° C., at a pressure of about 25 mm. of mercury, for 15 minutes. Attempted washing of the cooled reaction mixture with acetone was only partially successful in that swelling of the product caused difficulty in filtration. The reaction mixture was extremely soluble in water and was not precipitated by ethanol addition. Accordingly, after filtering the reaction

mixture to remove traces of water insoluble material it was concentrated. The crystalline solid which formed in the concentrated solution was dried, washed twice with absolute ethanol, filtered and dried to give the substantially pure 2-(sodium sulfo)ethyl 4-chloro-o-tolyloxyacetate, analyzing 10.52% chlorine as against 10.72% the calculated chlorine value for $C_{11}H_{12}ClNaO_5S$.

Example 4

10 This example shows esterification of 2,4-dichlorophenoxyacetic acid with sodium isethionate in the presence of an inert diluent. To a 1-liter reactor equipped with stirrer, thermometer, modified Dean and Stark trap, and a reflux condenser there was charged 400 g. of trichlorobenzene, 148 g. (1.0 mole) of sodium isethionate and 221.9 g. (1.0 mole based on 99.6% assay) of 2,4-dichlorophenoxyacetic acid. The charge was rapidly brought to a pot temperature of 192° C. and maintained at a temperature of 192-215° C. for a time of 2 hours and 50 minutes. During this time a total of 17.3 g. (96.2% of theory) of water was collected. At the end of the heating, the reaction mixture was poured rapidly, with stirring, into 1600 g. of water and the reactor was washed with hot water and the water washings combined with the main product. The whole was then allowed to stand overnight. The organic layer which formed upon standing was separated and the residual aqueous layer shaken with activated alumina and filtered to remove traces of insoluble material. One-half (1210 g.) of the filtrate was drum dried at 60 lbs. steam pressure to give 165.0 g. (94.4% theoretical yield) of the substantially pure 2-(sodium sulfo)ethyl 2,4-dichlorophenoxyacetate. One-fourth (605 g.) of the filtrate was neutralized with 6.2 g. of 40% sodium hydroxide, filtered and drum dried at 60 lbs. steam pressure to give 80.7 g. (92% theoretical yield) of the substantially pure 2-(sodium sulfo)ethyl 2,4-dichlorophenoxyacetate. Both products gave clear aqueous solutions.

Example 5

40 To a 1-liter, 3-neck reactor fitted with glass paddle, thermometer and take-over head there was charged 256.5 g. (1.0 mole) of 2,4,5-trichlorophenoxyacetic acid and 202 g. (1.05 mole) of sodium 2-(2-hydroxyethoxy)ethanesulfonate. The charge was heated to a temperature of 150° C. at which point it became fluid and water began to condense in the take-off condenser. Heating was then continued until a temperature of 250° C. was attained, and a water pump vacuum was then applied. After maintaining the reaction mixture for 15 minutes at 50 a temperature of 250° C. and a pressure of 22 mm. of mercury the loss in weight of the charge was determined to be 30.8 g. The reaction mixture, a liquid having a freezing point of 150-160° C. was stirred with 200 g. of acetone and filtered. There was thus obtained as the 55 precipitate the substantially pure 2-(2-sodium sulfoethoxy)ethyl 2,4,5-trichlorophenoxyacetate.

Example 6

60 This example describes testing of the herbicidal activity of the compounds prepared in Examples 1-3. Aluminum pan flats, filled with mixtures consisting of 2 parts of top soil which had been screened through a 1/4" wire mesh and 1 part of sand, were seeded to buckwheat, radish, wild oats and rye grass. Twenty seeds of each were used. The 65 grass seeds were scattered randomly over one-third the area of the soil surface and the seeds of the broad-leaved plants were randomly scattered over the remaining two-thirds of the soil surface. The seeds were covered with a 3/8" layer of the soil. The seeded pans were placed in 1/2" of water and allowed to absorb moisture through the perforated bottom until the soil surface was completely moist. The pans were then transferred to a wet sand-bench in the greenhouse for germination and growth. Respective 0.4 percent (by weight) aqueous solutions of 2-(sodium sulfo)ethyl 2,4-dichlorophenoxyacetate (Product 75

I), 2-(sodium sulfo)-ethyl 2,4,5-trichlorophenoxyacetate (Product II) and 2-(sodium sulfo)ethyl 4-chloro-o-tolyl-oxyacetate (Product III) were prepared. When the test plants in the pan flats were from 10 days to 2 weeks old, they were sprayed, respectively, by means of an atomizer, with 30 cc. of the solution. The sprayed pans of plants were then maintained in the greenhouse for 10 days. At the end of this time, observation of the sprayed plants showed the grass which had been sprayed with the solution of Product II and III to be entirely unharmed whereas that which had been sprayed with Product I showed slight injury. Broad-leaved plants which had been sprayed with the solutions of Product I and II were completely dead and those which had been sprayed with the solution of Product III showed severe injury.

Similar testing of Product I at a concentration of 0.13 percent showed no injury to grass at this concentration, whereas broad-leaved plants were completely dead.

Example 7

This example describes testing of the volatility characteristics of the compounds of Examples II and III, i. e., 2 - (sodium sulfo)ethyl 2,4,5 - trichlorophenoxyacetate (Product II) and 2-(sodium sulfo)ethyl 4-chloro-o-tolyl-oxyacetate (Product III).

Respective 1% aqueous solutions of each compound were prepared and 0.12 cc. of the solution of Product II was applied to a section of filter paper. To another filter paper there was applied 0.132 cc. of the solution of Product III, the quantity of solution employed in each case being gauged to provide comparable amounts of each chemical based on the acid equivalent.

Potted bush beans (Black Valentine variety) with first trifoliate leaves still unfolded were sealed in polyethylene bags (15" x 8") inside of which had been attached (at the top) one of the treated filter papers. The sealed pots were then maintained for 48 hours at a temperature of 75-85° F. After 48 hours the plastic bags were removed and the plants placed in wet sandbenches in the greenhouse. Observation of the plants 9 days after the plastic bags had been sealed to the pots showed no visible effect of the test chemicals upon the plants. On the other hand, in a similarly conducted test with butyl 2,4-dichlorophenoxyacetate the use of an equivalent quantity (0.12 cc.) of this ester showed the plants to be completely dead 9 days after pots of the bush beans had been sealed.

The very good water-solubility of the present esters is of economic significance in that it permits easy and inexpensive formulation. Unlike the prior water-insoluble esters of the "2,4-D" or "2,4,5-T" type, the present sulfoethyl esters need not be dispersed or emulsified for use as sprays. They may be packaged in solid form for the user to incorporate into water in the useful concentrations, or they may be sold in concentrated aqueous solutions which need be merely diluted with water prior to use. Neither organic solvents, emulsifying agents, or special formulating equipment is required.

While the present sulfoethyl esters are most advantageously employed as herbicides in aqueous solution, they may also be incorporated into solid carriers such as clay, talc, pumice and bentonite to give herbicidal compositions which may be applied to the living plants or to soil surfaces which are to be freed from broad-leaved plant growth. The present esters may also be mixed with liquid or solid agricultural pesticides, e. g., insecticides and fungicides. For specialty uses, oil-in-water emulsions of the sulfoethyl esters may be prepared, employing either ionic or nonionic emulsifying agents, e. g., the long chain polyalkylene glycols or the long chain alkyl sulfonates.

Because of the very high herbicidal efficiency of the present sulfoethyl esters, they are present in the herbicidal sprays or dusts in only very small concentrations, for example, in concentrations of from 0.01 percent to 1.0 per-

cent by weight. The sulfoethyl esters possess at least the herbicidal efficiency of the known "2,4-D" or "2,4,5-T" type of compounds, but their use requires neither special formulations nor precautions to prevent injury of wanted plants in adjacent areas.

What I claim is:

1. A sulfo-ester having the formula

15 in which R, R', R'' and R''' are selected from the class consisting of hydrogen, chlorine and alkyl radicals of from 1 to 4 carbon atoms and in which at least one of R, R', R'' and R''' is chlorine, x is a number of from 1 to 2, n is a number of from 0 to 1 and M is a water-solubilizing cation.

20 2. 2-(sodium sulfoethoxy)ethyl 2,4,5-trichlorophenoxyacetate.

3. 2-(sodium sulfo)ethyl 2,4-dichlorophenoxyacetate.

4. 2-(sodium sulfo)ethyl 2,4,5-trichlorophenoxyacetate.

5. 2-(sodium sulfo)ethyl 4-chloro-o-tolyl-oxyacetate.

25 6. A herbicidal composition comprising an inert carrier and as the essential active ingredient a phytotoxic quantity of a sulfo-ester having the formula:

35 in which R, R', R'' and R''' are selected from the class consisting of hydrogen, chlorine and alkyl radicals of from 1 to 4 carbon atoms and in which at least one of R, R', R'' and R''' is chlorine, x is a number of from 1 to 2, n is a number of from 0 to 1 and M is a water-solubilizing cation.

40 7. A herbicidal composition comprising an inert carrier and a phytotoxic quantity of 2-(sodium sulfo)ethyl 2,4-dichlorophenoxyacetate as the essential active ingredient.

45 8. A herbicidal composition comprising an inert carrier and a phytotoxic quantity of 2-(sodium sulfo)ethyl 2,4,5-trichlorophenoxyacetate as the essential active ingredient.

50 9. A herbicidal composition comprising an inert carrier and a phytotoxic quantity of 2-(sodium sulfo)ethyl 4-chloro-o-tolyl-oxyacetate as the essential active ingredient.

55 10. The method of destroying undesirable plants which comprises applying to said plants a phytotoxic quantity of a herbicidal composition comprising as the essential active ingredient a sulfo-ester of the formula:

65 in which R, R', R'' and R''' are selected from the class consisting of hydrogen, chlorine and alkyl radicals of from 1 to 4 carbon atoms and in which at least one of R, R', R'' and R''' is chlorine, x is a number of from 1 to 2, n is a number of from 0 to 1 and M is a water-solubilizing cation.

70 11. The method of destroying undesirable plants which comprises applying to said plants a phytotoxic quantity of a herbicidal composition comprising 2-(sodium sulfo)ethyl 2,4,5-trichlorophenoxyacetate as the essential active ingredient.

75 12. The method of destroying undesirable plants which comprises applying to said plants a phytotoxic quantity

11

of a herbicidal composition comprising 2-(sodium sulfo)-ethyl 4-chloro-o-tolyloxyacetate as the essential active ingredient.
